UNITED STATES PATENT OFFICE.

ROBERT H. GAYLORD, OF PASADENA, CALIFORNIA, ASSIGNOR TO R. H. GAYLORD COMPANY, OF LOS ANGELES, CALIFORNIA, A CORPORATION OF CALIFORNIA.

ELEVATOR-SIGNAL.

1,215,795.

Specification of Letters Patent. Patented Feb. 13, 1917.

Application filed August 12, 1915. Serial No. 45,093.

To all whom it may concern:

Be it known that I, ROBERT H. GAYLORD, a citizen of the United States, residing in Pasadena, and State of California, have invented a new and useful Elevator-Signal, of which the following is a specification.

This invention relates to telephonic signaling means of the type disclosed in my patent 1,185,085, granted May 30, 1916, 10 whereby the operators in the cars may make telephonic announcements at the different floors of the building.

One object of the present invention is to provide a signaling means of this type in 15 which a single announcing telephone receiver is used at each floor for both up and down signals.

Another object of the invention is to provide a signaling system of this type whereby 20 announcement may be made at a floor without depending on primary control by a passenger at such floor, by closure of a push button or otherwise.

A further object of the present invention 25 is to provide an elevator signaling means in which the same set of fixed contacts and circuits therefrom are used for signaling to the landing signals or announcing means in both up and down movements of the car.

Another object of the invention is to simplify the operating circuits for the telephonic means by elimination of retardation coils and condensers as far as practicable.

Another object of the invention is to provide, in connection with an elevator signal 35 in which a car signal is operated by an energizing circuit controlled from the different landings, means whereby the telephonic circuit is energized from said energizing circuit, at the same time maintaining operative independence of the car signal 40 from the telephonic means.

Another object of the present invention is to adapt a telephonic signaling means such 45 as disclosed in my application aforesaid for use with mechanical and electrical apparatus and circuits now in use. I have herein shown, for example, an adaptation of the telephonic signaling means to the apparatus 50 and circuits disclosed in patent to J. B. Smalley and C. A. Reiners, dated July 24, 1906, No. 826,752.

The accompanying drawings illustrate 55 embodiments of my invention, and referring thereto:

Figure 1 is a longitudinal section of the car-operated switch.

Fig. 2 is an inverted plan view of the switch means for controlling connection to the landing signals, taken on line 2-2 in 60 Fig. 1.

Fig. 2a is a detail section of the switch means for controlling the floor signals.

Fig. 3 is a transverse section on line 3-3 in Fig. 1. 65

Fig. 4 is a section on line 4-4 in Fig. 1.

Fig. 5 is a section on line 5-5 in Fig. 1.

Fig. 6 is a diagram of the circuit connections.

Fig. 7 is a diagram of the car signal means 70 and circuit.

Fig. 8 is a side elevation of the circuit closing and resetting means.

Fig. 9 is a diagram of a modification of 75 the car signal circuit.

Fig. 10 is an elevation of a modified form of car-operated switch, the circuit connections therefor being shown diagrammatically.

Fig. 11 is a front elevation of part of the 80 fixed contacts of the switch shown in Fig. 10, with the circuit connections therefor.

Referring to Figs. 1 to 5, the car-operated switch therein shown is similar to that disclosed in the Smalley and Reiners patent 85 above referred to, except that the contacts for the floor signals have been omitted, and a special switch means for that purpose substituted therefor. Said car-operated switch comprises a frame 1, a screw 2, mounted to 90 turn in said frame, and connected to the elevator operating mechanism so as to move in correspondence therewith; a movable switch member 3 carried by said screw, formed as a rocking cross arm having a screw threaded hub 3' fitting said screw, frames 4 and 4' pivoted at opposite ends of said cross arm and carrying respectively, pairs of movable contacts 5 and 5' for controlling the car-signal circuits, and fixed contacts 6, 7 and 6' 7' mounted on frame 1 for coöperation with the contacts 5 and 5' respectively. Switch member 3 is mounted to tilt on screw 2, under the frictional action of the screw, so as to bring the contacts 5 or 5' at one 100 side or the other in contact with the fixed contacts 6, 7, or 6', 7' as the case may be, according to the direction of motion of the screw, so that when the elevator car connected to said switch is moving down, the 105

110

pair of contacts 5' will slide on contacts 6' and 7' at one side of the switch, making connection therebetween, as shown in Fig. 3, while the contacts 5 at the other side will ride on the contacts 7 without making connection with the contacts 6, the construction and operation of these parts being the same as in the said patent. Contacts 7 and 7' are long feed contacts and contacts 6 and 6' correspond in number and position to the floors 10 of the building, connection thereto being controlled by circuit closers at the respective floors. In the present case, in conformity to the patent aforesaid I have 15 shown this control as effected through mercury cups 10 and 10' controlled by electromagnets 11 and 11' in circuit with push buttons at the respective floors, and resetting means are provided for these mercury cup 20 circuit closers, comprising series of contacts 8, 9 and 8', 9', at opposite sides of the switch, coöperating with pairs of contacts 12 and 12' on the respective plates 4 and 4' and connected to control resetting magnets 13 and 25 13' for the mercury cup circuit closers, as in said patent. The rocking movement of the member 3 is controlled by guide means, consisting of track rails 15, 16 and 17 forming two ways for a shoe 18 on an arm 19 extending from said member 3, suitable means, as 30 shown in said patent, being provided for guiding the shoe from one to the other of said ways when the arm is rocked by reversal of motion of the screw at either end 35 of its travel.

My special switch means for controlling the floor signal circuits comprises a double series of contacts 22 and 22', mounted on an insulating switch board 24 at the top of the 40 car-operated switch, and a switch member 25 carrying contacts adapted to coöperate with the contacts 22 and 22', and operated by the main switch member 3. For this purpose the member 3 may have a projection 45 27 which engages between lugs 28 on member 25, so as to move the member 25 longitudinally with the member 3. Member 25 is formed as an insulating plate, carrying contacts 34, 34' and 35, 35' and mounted to 50 rock on pivots 29 on metallic shoes 30, 30' which slide in metal tracks or guides 31, 31', and are held into frictional engagement with said tracks by a spring 32 which extends in a bore 33, between the ends of the pivot portions 55 29 of the shoes, insulating washers 20 and 20' being inserted between spring 32 and pivot portions 29. The lugs 28 on member 25 are below the pivots 29 so that when the member 3 is moving in one direction, say 60 for "up" travel of the elevator car, the projection 27 on member 3 engages one of said lugs to tilt the switch member 25, so that contact 34 and 34' at the forward end of member 25 will ride on the series of fixed 65 contacts 22 and 22', and when the motion of

member 3 is reversed, for "down" travel of the car, the member 25 will be tilted to bring the contacts 35 and 35' at the other end thereof, into riding engagement with contacts 22 and 22', the contacts 34 and 34' 70 being at this time removed from riding engagement with contacts 22 and 22'. Contacts 34, 34' and 35, 35' may be formed as pins sliding in holes in member 25 and having heads 37 at their lower ends engaged 75 by springs 38 to press the contacts 34, 34' and 35, 35' toward the respective contacts 22 and 22'. The springs 38 for each pair of contacts 34 and 35 and 34' and 35' may each be formed of a single strip of spring metal 80 connected by a wire 39 or 39' to the adjacent shoe 30 or 30', so that contacts 34 and 35 are connected to shoe 30 and contacts 34' and 35' are connected to shoe 30'. In addition to the series of contacts 22, end contacts 36 and 37 are provided at the ends of such series, and end contacts 36' and 37' are provided at the ends of the series of contacts 22', these end contacts being shown as comparatively long. 90

In connection with my improved telephonic signaling system I provide means whereby the telephone talking circuit is energized from a circuit in the car which may be a signal circuit, or a lighting circuit. 95 In the form of the invention illustrated in Fig. 6, the energizing circuit is the circuit for the car light or lamp 40 that serves as a signal for the operator. The telephone transmitter 41 in the car is preferably of 100 the duplex type shown, comprising a diaphragm 42, see Fig. 7, located in an insulating casing 41, in position to receive the sound waves from a mouthpiece 44, and connected by an insulating pin 45 to a metallic diaphragm 46 located between two conducting plates 48 and 47, carbon 49 being interposed between the diaphragm 46 and each of the plates 47 and 48, and held in position by means 50 permitting of vibration of diaphragm 46. Diaphragm 46 is connected to one side 51 of the energizing circuit and the other side 52 of said circuit is connected to two branch wires or connections 53, 53' leading to reactance or retardation coils 54, 54', from which wires 56 and 56' respectively lead to the transmitter plates 48 and 47. Wires 60 and 60' connect wires 56 and 56' respectively to condensers 61 and 61' from which wires 62 and 62' lead to the 110 telephone connections, hereinafter described. The telephone transmitter is thus energized from the lamp circuit 51, 52 by the connections through the retardation coils 54 and 54', but the connection between the energizing circuit and the telephone line wires 62 and 62' includes not only the retardation coils 54 and 54' but also the condensers 61 and 61' so that on the one hand, the energizing current being direct current (or of rela- 115 120 125 130

tively low frequency if alternating current) cannot pass to the telephone line wires 62 and 62' on account of the condensers in the connection, and on the other hand, the telephonic current is kept from passing in sensible amount to the energizing line by the inductive resistance of the retardation coils.

The resistance of the carbon in the transmitter 41 is sufficient to insure that when 10 two or more of the transmitters are simultaneously in connection with the telephone receiver at the landing, the telephonic current from any transmitter will not be short-circuited by any other transmitter, thereby 15 preventing the landing receiver from being rendered inoperative under these conditions.

In addition to the telephone transmitter 41, and the signal lamp 40 each elevator car may be provided with a disabling switch 20 64, for opening the resetting connections so that a call will be left for a succeeding car if desired; and also with a switch 65 for closing the talking circuit energizing connections independently of the circuit closers 25 at the landings, so that the operator may call all landings as he approaches them.

At each landing a telephone receiver 66 is provided, the same being preferably a loud talking or announcing telephone receiver, so 30 that the call or announcement given by the operator may be heard throughout the part of the landing or hallway adjacent to the elevators, and in the form of my invention shown in Fig. 6, each landing or floor is 35 further provided with circuit closer means, consisting for example, of a "down" push button 67 at the top floor, and "up" push button 68 at the bottom floor; and an "up" push button 69 and a "down" push button 69' at each of the intermediate floors, said push buttons 69 and 69' for each floor co-operating with a contact 69.

A car-operated switch as above described is provided for each elevator shaft and 45 located for example adjacent to the top of the shaft. The circuit closers 10 and 10' may be located adjacent to the top of the shafts, it being understood that one set of such circuit closers is sufficient for all the 50 shafts. Each of such circuit closers may consist of a mercury cup 109 and a contact lever 110, co-operating therewith and carried by or formed as the armature lever of electromagnet 13, said lever tending to move to closed position by gravity and being moved to open position by operation of said electromagnet 13. When so moved to open position it is held in such position by the armature 111 of electromagnet 11, until said 60 armature 111 is released therefrom by energization of said electromagnet 11. The circuit connections are as follows, as shown in Fig. 6: A wire 70 leads from a battery or source of current indicated at 71, to a 65 switch 72, whence a wire 73 leads to one

side of each of the push buttons, both for the up and down calls, at each floor. The "up" push buttons for all the floors except the bottom floor, are connected respectively by wires 74 to the respective electromagnets 70 11 for the mercury cup circuit closers 10, at the "up" side of the car-operated switch, and wires 75 lead from said magnets to a wire 76 connected to a wire 77 which leads to the other side of the battery 71. A wire 75 80 leads from battery wire 70 to the disabling switch 64 in the car, whence a wire 81 leads to the long resetting contacts 9 at the up side of the car-operated switch. The contacts 8 of said switch are connected by 80 wires 82 to the respective resetting electromagnets 13, from which wires 84 lead to a wire 85 connected to the battery return wire 77. The "down" push buttons for all the floors except the top floor are similarly 85 provided with connections 74' to the respective electromagnets 11' at the "down" side of the car-operated switch, the connections for said electromagnets being completed by wires 75' and 76' to the battery return wire 90 77. The resetting connections for the "down" side lead from wire 81, by wire 81' to the long contact 9' and from the contacts 8' by wires 82' to resetting electromagnets 13' and from said electromagnets by wires 95 84', 85' to battery return wire 77. The push buttons for the top and bottom floors are connected to a wire 87 leading through resistance 88 to the wire 76' connected to the battery return wire 77. All of these connections are, or may be, substantially the same as in the patent above referred to, these constituting the controlling connections for the mercury cup circuit closers. The circuits for the signal means proper are energized 100 by another source of current, indicated at 90, which may be a generator or supply circuit adapted to supply current suitable for energizing the signal lamp 40 in the car. A wire 91 leads from said current source to the 110 signal lamp 40 in the elevator car, from which a wire 52 leads to the telephone transmitter 41 as above described. From said transmitter a wire 51 leads to switch 65, from which a wire 93 leads to the long signal contact 7 at the "up" side of the car-operated switch. Contacts 6 of said switch are connected by wires 94 to the respective mercury cup circuit closers 10, whence a wire 95 leads to current source return wire 96. 115 A wire 93' leads from wire 93 to the long signal contact 7' at the "down" side of said switch, contacts 6' being connected by wires 94' to the respective mercury cup circuit closers 10', whence a wire 95' leads to return wire 96. A wire 97 leads from return wire 96 to a normally open contact 65' of switch 65. The telephone transmitter 41 is connected by wire 62 to track 31 at one side 120 of my special switch means, and contacts 22 130

at the same side are connected by wires 99 to the telephone receivers 66 at the different landings, whence wires 99' lead to contacts 22' at the opposite side of said switch means. 5 From track 31', a wire 62' leads back to telephone transmitter 41. A telephone receiver 100 may also be placed in each car, and connected to wires 62 and 62'. 101 indicates a bell, normally shunted by switch 10 72, but included in circuit, by opening said switch, so that the bell will be sounded whenever a push button is operated, the object of the bell being to call to the attention of the operators the fact that a passenger 15 wishes to be taken either up or down.

The fixed contacts 22, 22' of the car-operated switch, or the wires 99, 99' leading thereto, are cross connected by wires 102, 102' to corresponding contacts or wires in 20 the car-operated switches for all the other cars. Similar cross connections will be provided for the controlling contacts 6 of the car-operated switch, as in the patent above referred to. The wires 80, 81, 91, 93, 97, 62 25 and 62', leading to the car will be mounted in flexible cables or otherwise so as to maintain connection with the car in its travel.

The operation of the form of my invention above described is as follows: Assuming that 30 one of the "down" push buttons is closed, for example, the button 69' for the fourth floor, as shown in Fig. 6. Current will then flow from battery 71 through wire 70, switch 72 and wire 73 to push button 69', thence by 35 one of the wires 74' to the electromagnet 11' corresponding to the fourth floor and from said electromagnet by wires 75' to wire 76' and thence by wire 77 back to battery 71. Electromagnet 11' being thus energized, attracts its armature 111 and allows the circuit closer lever 10 to fall into mercury cup 109. When any elevator car, in its descending 40 movement approaches within, say, two floors of the fourth floor, its contacts or brushes 5' close connections between the contact 7' and the contact 6' corresponding to such floor, and a car-signal circuit is then closed as follows: from current sources 90 through wire 91 signal lamp 40, wire 52, then in parallel 45 through both wires 53, 53', both retardation coils 54, 54' and wires 56, 56', and both parts of the duplex telephone 41 to the central member 46; thence through wire 51, switch 65, and wires 93 and 93' to long contact 7' 50 of the car-operated switch, through the pairs of brushes or contacts 5' to the contact 6' above referred to, and thence through wire 94' to the operated mercury cup circuit closer 10, and from said circuit closer by wires 95' 55 and 96 back to the current source 90. This current energizes the signal lamp 40 thereby notifying the operator that a passenger is calling on the fourth floor or a floor immediately in advance of his car, requiring a stop, 60 and as this current passes through the tele-

phone transmitter it energizes the same so as to put it in condition for transmitting a call to the calling floor. If the operator intends to stop at the calling floor in response to this call, he will speak into the transmitter 41, 70 an announcement, such as "Number two car down" and this announcement will be transmitted to the telephone receiver 66 and announced by the said telephone receiver, the current passing from telephone transmitter 75 41 through condenser 61 wire 62, to track 31 for the car operated switch, thence through shoe 30, wire 39 and spring 38 to the contact pin 35 at one side of the switch member 25. As the car is descending at this 80 time, this switch member is operated by the projection 27 of the main switch means so that it is tilted forward and the forward pins 35 and 35' thereon make contact with the fixed contacts 22 and 22' which correspond to a floor in advance of the car, say to the second floor below the car, and the connection for the current will be continued from forward contact pin 35 to such contact 22, thence by wire 99 to the telephonic receiver or announcing telephone 66 at the said floor, which is the floor that has given the signal for a stop. From said receiver the current passes through wire 99' back to a switch contact 22', and through the forward contact pin 35', spring 38', wire 39', shoe 30', track 31', wire 62' and condenser 61' back to the telephone transmitter 41. The sound waves impressed on the diaphragm 46 of the transmitter, cause the diaphragm 46 to move so that the resistances of the carbon bodies at either side of the diaphragm are inversely varied, so as to produce inequality in the drop and inequality in electromotive forces on the wires 56 and 56' at 90 opposite sides of the transmitter, resulting in a differential electromotive force which is impressed through the condensers 61 and 61' on the telephone connections as stated, causing the announcement which is spoken into the transmitter to be announced by the receiver at the calling landing. As the car continues to descend, the contact pins 35 and 35' aforesaid pass off of the fixed contacts 22 and 22' corresponding to the calling floor, 105 and break the telephonic connection, but the length of these contacts is such as to provide for maintenance of connection while the car is traversing the height of, say, somewhat more than one story of the building. In 110 such continued descent of the car, the brushes 12' on the main car-operated switch make connection between the long contact 9' and the resetting contact 8' corresponding to the calling floor, thereby closing a circuit from the battery as follows: through wire 80, switch 64, wires 81, 81', contact 9', brush 12', contact 8', wire 82', resetting electromagnet 13' for the fourth floor, and wires 84', 85' and 77 back to battery 71. The current 115 120 125 130

through this circuit energizes resetting magnet 13' and causes the armature thereof to be attracted, opening the mercury cup circuit closer 10' and said circuit closer is then held in open position by the armature of the electromagnet 11', the latter electromagnet being at this time deenergized by reason of the open condition of its circuit at the push button. This completes the signaling operation, 10 the circuits being then in normal condition.

If at any time the operator cannot take on the calling passenger, he may move switch or push button 64 in the car, thereby opening the resetting circuit just traced, and at the same time he may announce to the calling floor through the telephonic connections above described, that some other car will respond to the call. It will be seen that if two or more cars are in position to talk to any given floor at the same time, the operators thereon may communicate with one another by the said telephonic communications, corresponding fixed contacts on the car-operated switches for different cars being all cross-connected, so that any telephonic current passing from either transmitter to the contacts 22, 22' of the corresponding car-operated switch, will through the cross connections 102, 102', pass to the telephone lines 62, 62' of said other car, and the announcement may be heard at, or announced by the receiver 100 in such other car.

By moving the switch 65 over to the normally open contact 65' the operator may energize his pilot light regardless of whether any landing push button has been closed, and thereby energize the telephone transmitter in his car, independently of such push buttons. By this means he may make an announcement at a floor in advance of the car, whether said floor has called or not, and the signal system may by this single switch be converted at any time to a strictly schedule system as required for department stores wherein the general practice is to stop the car at each floor; or if desired the system may be run during certain hours on such schedule stops, and at other times on call stop, by changing the switch 65 from contact 65' to normal position shown in Fig. 6.

When the car reaches the bottom of the shaft and reverses its movement, the shaft or screw 2 also reverses its rotative movement, with the result that the switch member 3 is moved reversely along the screw and is also tipped to the other side so as to make connection for the "up" contacts as in the patent referred to. At the same time, the projection 27 on said switch member engages the lugs 28 on switch member 25 to tilt the said member 25 so as to bring the contacts 34 and 34' on the other end, which is now the forward end, into riding engagement with the contacts 22 and 22' on the

switch board, so that connection is still produced to the announcing telephones in advance of the car.

Any suitable transmitter may be used for receiving electric energy from the car signal or other supply circuit and transmitting telephonic impulses to the telephonic circuit, while maintaining the operative independence of such circuits. For example, the transmitter shown in Fig. 9 may be used, comprising two duplex telephones 137 and 138, similar to the one above described, having their outer conductors 140, 141, 140' and 141' reversely connected by wires 128 and 129 to the supply leads 130 and 131, and having their intermediate diaphragms 132 and 133 connected by wires 134 and 134' respectively to condensers 135 and 135', which are in connection with the telephonic circuit wires 136 and 136'. Sound waves impressed simultaneously on the two transmitting devices 137 and 138 produce reverse changes in the drop at the two sides of the circuit, resulting in impulses being sent over the telephone line.

I am aware that elevator signal systems have heretofore been used wherein moving contacts travel back and forth on a series of fixed contacts, but in these systems independent switch means are provided to make a portion of such contacts inoperative, by disconnection of the common supply circuit. An important feature of my invention as above described, is the provision of a car-operated switch, namely, the switch comprising the fixed contacts 22 and 22' and the switch member 25 with the contacts thereon, which makes connection for signaling or communicating, in both the up and down movements of the car, by means of the same set or series of fixed contacts, the moving contacts traveling in the same path in both up and down movements. When said connection is made with any of said fixed contacts the corresponding landing announcing or signaling device becomes receptive to announcements or signals whether the car is traveling up or down. This simplifies the construction and wiring of the switch, as far as the function of announcing or signaling at the landings is concerned. This feature of my invention, as well as the telephonic communication in the manner above described, is applicable in connection with any form of car-operated switch and either in conjunction with, or independently of, any car signal means. In Fig. 10, I have shown a simple embodiment of the invention, comprising a switch similar in all respects to the switch 25 above described, and arranged vertically, so as to be moved up or down by engagement of a vertically moving actuator 113 with projections 114 on the tilting member 115 of said switch. Said actuator consists of a flange on a vertical

tube 116 mounted to telescope on a fixed vertical tube 117, said tubes inclosing a spring 119 which is connected at opposite ends to the tubes, so as to draw them together. A 5 suitable flexible weighted member, for example a cable, is connected to the elevator car 118 and to the lower tube 116 so that in the ascent and descent of the car more or less of the weight of the cable will be suspended from this tube and the tube will 10 therefore be drawn down, against the action of spring 119, as the car descends, and will be raised by the spring as the car ascends. This motion of the tube 116 is communicated to the switch member 115 through the 15 members 113, 114 aforesaid, resulting in tilting said switch member on the carrying means or shoes 120 and in causing the shoes to travel in tracks 121 so as to move the contact pins 122 on said switch member along the fixed contacts 123. Said fixed contacts are connected by wires 99 and 99' to the 20 announcing telephone receivers at the respective floors. The contact pins 122 on switch member 115 are connected by springs 25 124 to wires 125 leading through the cable or independently thereof, to the telephone transmitter 141 in the car, which is similar to the transmitter 41 above described, but in this case is energized by connections 126, 126' directly from the car-lighting circuit 30 wires.

One of the important advantages of the present invention is the notable saving in cost of material and labor, as regards that part of the system relating to the signaling to the waiting passenger. It will be seen that for the connections from the car-operated switches to the floor signals but two 35 wires are required at each floor landing for the entire bank of cars, and but one "fixture", (in this case a telephone receiver), as compared with systems now in use which require for the connections from the car-operated switch to the floor signals two 40 wires for each hatch opening, besides one common wire, and also a fixture for each opening. A further saving is effected by my invention in that the wiring for the 45 landing signals, including the connection to the car transmitter may conform to standard telephone practice, paired wires being used which are relatively inexpensive compared with the wiring required for the 50 usual signal lamps. By using twisted pair wiring the further advantage is secured that both sides of the circuit have the same resistance and capacity and the inductive influence of extraneous currents is avoided. 55 This construction, being according to well known telephone practice, is not shown in the drawings, the wires being shown separate, for clearness of illustration.

What I claim is:

60 1. An elevator signaling system compris-

ing a car signal, landing circuit closers, a car operated switch, electric circuit means controlled by said circuit closers and by the car operated switch to operate the car signal as the car approaches a landing at which the circuit closer has been operated, a telephone transmitter in the car, telephone receivers at the landings, fixed contacts connected with said receivers, a switch member operated by the aforesaid car-operated 70 switch and coöperating with said fixed contacts and connected to the said transmitter in the car, to operate the receiver at any landing from said transmitter as the car approaches such landing.

2. An elevator signaling system comprising a car signal, landing circuit closers, a car operated switch comprising separate series of fixed contacts for up and down movement of the car, and movably mounted 85 switch means provided with contacts to co-operate with said up contacts in the up movement of the car and with contacts to coöperate with said down contacts in the down movement of the car, another series 90 of fixed contacts, a movably mounted switch member adapted for operation by the aforesaid switch means and provided with contacts to coöperate with said last named series of contacts in both the up and down 95 movements of the car, and call receiving means at the different landings connected to said last named series of contacts to receive current from the same contacts in both up and down movements of the car.

100 3. An elevator signaling system comprising a car signal, circuit closers for different floors, a car-operated switch comprising separate series of fixed contacts for up and down movement of the car, and a movably mounted switch means provided with contacts for coöperation with the said up contacts in the up movement of the car and with contacts for coöperating with said down contacts in the down movement of the car, electrical connections controlled by said circuit closers and by said contacts of the car operated switch to operate the car-signal as the car approaches a landing for which the circuit closer has been operated, a telephone transmitter in the car, telephone receivers at the landings, a series of fixed contacts connected to said receivers and a movably mounted switch member adapted for operation by the aforesaid switch means and provided with contacts for coöperation with the last named series of contacts in both the up and down movements of the car.

115 4. In an elevator signaling system, call receiving devices at the landings and a car-operated switch comprising a series of fixed contacts arranged in two rows, opposite contacts in the respective rows being respectively connected to opposite sides of the 120 respective call receiving devices, a movably 125 switch member adapted for operation by the aforesaid switch means and provided with contacts for coöperation with the last named series of contacts in both the up and down movements of the car.

- mounted switch member adapted for operation in opposite directions by the up and down movements of the elevator car, and provided with contacts for coöperation with the said series of contacts in both directions of movement, and signal transmitting means in the car connected to said contacts on said movably mounted switch member.
5. In an elevator signaling system, telephone receivers at the landings and a car-operated switch comprising a series of fixed contacts connected respectively to said receivers, a movably mounted switch member adapted for operation in opposite directions in a single path by the up and down movements of the elevator car and provided with contacts for coöperation with said series of contacts in both directions of movement, and a telephone transmitter in the car connected to said contacts on the movably mounted switch member.
6. In an elevator signaling system, a car signal, a circuit for energizing the same, a transmitter in the car, connections including reactance means for energizing said transmitter from said signal energizing circuit, a telephonic receiver and connections including condenser means between said transmitter and said receiver, whereby the telephonic devices are energized from the signal operating circuit but the telephonic and signal circuits are independent in operation and a car-operated switch controlling the circuit for the signal and also controlling the connections for the telephonic receiver, so as to establish the telephonic connection when the signal is energized.
7. In an elevator signaling system, a car-operated switch comprising a series of fixed contacts corresponding to different floors, means mounted to slide in opposite directions in the same path in the up and down movements of the car, switch means movably mounted on said sliding means and carrying contacts adapted to engage with the said series of fixed contacts in both directions of movement of said sliding means, and car-operated means engaging said switch means to change its position on the said sliding means as the movement of the car is reversed, so that the contacts on said switch means engage with fixed contacts for a floor in advance of the position of the car, in either direction of movement of the car.
8. In an elevator signaling system, a car-operated switch comprising a track means, carrier means mounted to slide frictionally in said track means, a switch member mounted to rock on said carrier means, and carrying contacts arranged in different longitudinal positions thereon, fixed contacts arranged in the path of the aforesaid contacts, and car-operated means for engaging with said rocking member to rock the same to bring the more advanced contacts thereon into coöperating relation with the fixed contacts, and to move the rocking member with its carrying means longitudinally on said track means.
9. In an elevator signaling system, a single call receiving means at each floor for up and down calls, a plurality of elevator cars provided with call transmitting means, and means comprising connections from the call transmitting means of all the cars to each call receiving means adapted to maintain receptive condition of such call receiving means for a call from the transmitter in any car after said call receiving means has responded to a call from the transmitter in another car.
10. In an elevator signaling system, a single call receiver at each landing for receiving both up and down calls, a car, a car operated switch comprising a series of contacts connected respectively to said call receivers, and a switch member adapted to coöperate with the said series of contacts in both up and down movements of the car, and means connected to said switch member for supplying current thereto for operating the call receivers.
11. In an elevator signaling system, a call receiver at each of a plurality of landings, a car, a call transmitter on a car, and a car-operated switch and connections controlled thereby for connecting the transmitter to the receiver at any landing as the car approaches the same from either direction.
12. In an elevator signaling system, a telephone receiver at each of a plurality of landings, a car, a telephone transmitter on a car, and a car-operated switch comprising contacts connected to said receiver and a switch member operated by the car and adapted to coöperate with the same contacts in either direction of movement of the car to connect said transmitter in the car to the same receiver at a landing in both up and down movements of the car.
13. In an elevator signaling system, telephone receivers at the landings, a car, a telephone transmitter in the car, a car-operated switch provided with contacts connected to said receivers, and direct connections from the transmitter in the car to the car-operated switch, whereby the connection between the transmitter and the receivers may be controlled only by the car-operated switch.
14. In an elevator signaling system, a plurality of cars, telephone transmitters in the cars, telephone receivers at the landings, and means comprising connections maintaining operative communication between said transmitters and the receiver at any landing when the car is adjacent to such landing.
15. In an elevator signaling system a plurality of cars, telephone transmitters in the cars, telephone receivers at the floor landings, circuit closers for the floor landings,

- a car-operated switch, means comprising circuit connections controlled by said circuit closers and said car-operated switch, to establish communication between said transmitters and receivers, and a switch and connections controlled thereby for closing connection between the transmitters and the receivers independently of the said circuit closers for the landings.
- 10 16. In an elevator signaling system, a plurality of cars, telephone transmitters and receivers in the cars, a landing receiver, a car-operated switch and circuit connections controlled thereby to put the telephone transmitters and receivers of different cars simultaneously in connection with a landing receiver, whereby the telephonic call given by the operator in one car may be heard by the operator in another car.
- 15 17. In an elevator signaling system, a car, a call transmitter in a car, a car-operated switch, a floor landing call receiving device, and circuit connections controlled by said car-operated switch, whereby the floor landing call receiving device is made receptive to signals from the call transmitter in the car, by the movement of the car in either direction.
- 20 18. In a multiple car elevator signaling system, a plurality of cars, a single call receiving device at each floor, and means controlled by the movement of the cars for making said call receiving device receptive to calls from all the cars, in either direction of travel of the cars.
- 25 19. In an elevator signaling system, a plurality of cars, a car-operated switch, a call transmitter in each car, and a single call receiver at a landing, connected to said switch, so as to be receptive to calls in either direction of movement of said car, the same circuit connections serving for operation of the said call receiver in either direction of movement of said car.
- 30 20. In an elevator signaling system, a plurality of cars, a car-operated switch, means comprising circuit connections and including call transmitters in different cars, and a single receiving device at a landing receptive to signals from any of the call transmitters, independently of the operation of the other call transmitters.
- 35 21. In an elevator signaling system, a plurality of cars, a car-operated switch, means comprising circuit connections and including call transmitters in different cars, and a single receiving device at a landing adapted to receive signals from more than one of said call transmitters in the cars, in such manner that operation of said call receiving device by any call transmitter will not interfere with the receptiveness of said call receiving device to a signal from any other call transmitter.
- 40 22. In an elevator signaling system, a plurality of cars, a car-operated switch, means comprising circuit connections and including call transmitters in different cars, telephone receivers at the landings, telephone transmitters in the cars, and an energizing circuit for energizing said transmitters independently of manual control by the car operators.
- 45 23. In an elevator signaling system, a plurality of cars, a car-operated switch, means comprising circuit connections and including call transmitters in different cars and circuit closers at the landings, telephone receivers at the landings, telephone transmitters in the cars, an energizing circuit for said transmitters, and circuit closers in the cars, whereby a car circuit closer or a landing circuit closer may collectively or independently energize one of the car transmitters.
